UNITED STATES PATENT OFFICE.

GEORG EMIL MATHIASSEN, OF COPENHAGEN, DENMARK.

IRONING MACHINE.

Application filed April 28, 1925, Serial No. 26,444, and in Denmark July 12, 1924.

My invention relates to a machine for ironing of all kinds of washing, also of full shirts.

My invention is illustrated in the accompanying drawing, in which

Figure 1 shows the machine in side view, partly in section; and

Figs. 2 and 3 details, respectively in front view and in top view.

A stand 1 carries a table 2, wherein is lodged a slide 3, on which is mounted the lower iron 4 of the ironing machine, the iron 4 resting partly on balls 5, partly being supported by spring-urged bolts 6, so that it gets a certain mobility about its longitudinal axis. The upper iron 7, being longer than the lower one, is suspended in arms 8 rotatable on a shaft 9, about which the iron 7 by means of a handle 10 can be swung in the direction of the arrow, so as to be brought in the position 7^a limited by stops 26. The upper as well as the lower iron can be heated for instance by gaspipes 11. The lower iron has a suitable covering 12, rendering it serviceable as an ironing underlayer, while the upper iron has a semi-circular recess 13, Fig. 3, corresponding to the foremost part of the band of a full shirt, and in front of which on the table 2 a suitable supporting arrangement forming no part of my invention may be placed, co-operating in well known manner during the ironing of the shirt-front with the recess 13 to shape the band. During this part of the ironing the slide 3 stands still in the position shown by full lines in Figs. 2 and 3, while the slide, when the ironing of the shirt-front is finished, by means of a handle 14 or the like is shifted to the position 3^a, so that the lower iron 4 no longer registers with the recess 13 and so is not hit by this, when the upper iron, after lifting, is brought down in the working position, the kind of washing being changed.

By lifting of the upper iron 7 after disconnection of a locking pedal 25 of well known kind, a pedal 15 is brought up in the position 15^a, being, by a combination of bars 16, 17, 18, influenced from a shaft 19, following the movement of the upper iron. With the bar-combination is, by a link 20, connected an angle lever 21 or the like, the position of which can be altered by turning a nut 22 on a screw-rod 23, so that the pressure exercised by treading down the pedal

15, when the upper iron by means of the handle 10 is brought in working position, can be varied.

When for instance a shirt has to be ironed, 60 beginning with the front part, and the co-acting irons beforehand are heated, the upper iron is lifted with the handle 10, and the slide 3 brought in the position shown by full lines, the shirt-front, which is not quite dry, is spread out on the covering 12 of the lower iron, and the arrangement for holding the band of the shirt at the same time brought in position. Thereupon the upper iron is sunk, so that the recessed portion 13 grasps about the band of the shirt, 70 whereupon the pedal 15 is pressed down from the position 15^a to that shown by full lines. By the pressure thus effected on the material, the ironing is accomplished. 75

The upper iron having been lifted again, the slide is slid through an opening 24, Fig. 3, in the table to the position 3^a, and the different parts of the shirt are successively spread out on the covering of the lower iron and ironed by sinking of the upper one and treading down of the pedal, 80 till the ironing is finished. The slide remains in the position 3^a during the ironing of all other parts of the washing than just 85 shirt- and collar-fronts, the recess 13 being inactive, as long as the slide rests in the said position.

As to details my machine may be varied 90 without departing from the principle of the invention, the upper iron for instance may be movably arranged about its longitudinal axis instead of the lower one.

Having thus described my invention, I 95 claim:

In ironing machines in which a swingable upper iron operated by means of a lever and pedal connection co-acts with a lower iron, the combination of an upper iron having a terminal recess, with a lower iron 100 shorter than the upper iron, and a handle provided with means for adjusting the lower iron in a longitudinal direction relatively to the upper iron to render the recessed portion of the upper iron either cooperative or noncooperative with the lower iron when the upper iron swings down on the lower iron, for the purpose specified. 105

In witness whereof I have hereunto set 110 my hand.

GEORG EMIL MATHIASSEN.
